UNITED STATES PATENT OFFICE.

CHARLES A. KRAUS, OF NEWTON HIGHLANDS, AND ROY D. MAILEY, OF LYNN,
MASSACHUSETTS.

VAPOR ELECTRIC APPARATUS.

1,046,081.

Specification of Letters Patent.

Patented Dec. 3, 1912.

Application filed August 27, 1909. Serial No. 514,908.

To all whom it may concern:

Be it known that we, CHARLES A. KRAUS and Roy D. MAILEY, citizens of the United States, and residents of Newton Highlands and Lynn, in the counties of Middlesex and Essex and State of Massachusetts, have invented new and useful Improvements in Vapor Electric Apparatus, of which the following is a specification.

0 Our invention relates to the construction of vapor electric apparatus and has for its object the provision of structural features which shall insure efficiency and durability and capacity for preserving continuity of 5 operative conditions while carrying electrical currents larger than have heretofore been considered feasible in such apparatus.

Particularly, these improvements relate to the construction and attachment of the electrodes and electrode leads which constitute 0 essential factors in vapor electric apparatus.

As a typical example of vapor electric apparatus we take for purposes of description a vapor rectifier in which the characteristic 5 members are a container, hermetically sealed so as to include highly rarefied mercury vapor, at least two anodes and one cathode, and leads for these electrodes which pass through the walls of the container.

0 While it has been proposed to employ metal as the material for containers of vapor electric apparatus, so far as we are informed, the only practically effective apparatus of this class heretofore used, have employed glass as the material of which the 5 container is composed. It is difficult, indeed commercially impracticable, to construct a rectifier of large capacity while employing a glass container; breakage in handling and 0 transportation of such instruments, even those of the capacities considered practical, has proved a prolific source of loss; a glass container for such an instrument as a rectifier is by its nature and under the conditions 5 of operation a delicate apparatus, since its interior is exhausted to very low pressure and contains also a body of liquid mercury which, under the vacuum conditions, is liable to break the container unless the apparatus be handled very carefully. Moreover, owing to the difficulty of sealing electrode leads of large dimensions through the glass walls of a glass container, it has not been found feasible, so far as our experience 5 and observation go, to construct efficient

glass rectifiers capable of converting current substantially greater than 50 amperes. The chief difficulty which has embarrassed constructors of metal contained rectifiers and kindred apparatus is inherent in the construction of the electrode leads and connections. Obviously current must be led to the electrode within the container through connections which are effectively insulated and which at the same time do not impair the essential hermetic closure of the container. So far as we are informed, the only technically effective solution suggested to meet this difficulty has been to lead the current through columns of mercury at atmospheric height, and those who are familiar with the demands of industrial and commercial conditions will recognize the practical disadvantages of such an arrangement; moreover, we believe it to be doubtful if the necessary vacuum to be maintained in a rectifier can be successfully preserved when a system of mercury sealed leads is employed. The necessity for effective gas-tight insulating joints for the electrode leads employed by the usual container has been recognized as, for instance, in Austrian Letters Patent No. 19,023, issued Jan. 25, 1905, to Cooper Hewitt Electric Company, and U. S. Patent No. 760,483, dated May 24, 1904, to Van Recklinghausen, in which, however, the only suggestions as to practice are either a mercury seal between a metal bottom and a glass top of a vapor electric container, or non-conducting bushings which are described as made tight in a metal lid which is either ground into the neck of the container or united therewith in some other manner, the detailed or specific manner of making gas-tight joints being otherwise left to the imagination. We have demonstrated to our own satisfaction that mercury seals, ground joints and cemented joints are incapable of producing effective practical results, and the subject matter of this specification relates particularly to the construction of electrode lead connections in combination with a metal container which has effectively met the requirements of practice. The within described invention therefore is characterized by the employment of insulating joints wherewith the electrode leads are hermetically sealed to a metal container so as to secure effective insulation and to maintain the gas-tight con-

dition essential to the operation of the apparatus; broadly speaking, these joints consist of metallic members and a refractory insulating member either wholly or superficially vitreous so as to be gas-tight, the insulating member adhering to the metallic members by means of a flux vitreous in its character which fuses at a relatively moderate temperature and which should possess, 5 moreover, when heated, the effect of dissolving the oxid of the metal which composes the metal member and of wetting and adhering to the metal with the greatest intimacy. A composition or compositions of 10 matter well adapted for use as the non-metallic members of such joints and also sundry peculiarities of the joints themselves, 15 form the subjects matter of applications for Letters Patent of the United States Serial Nos. 514,858 and 514,859, filed on or about 20 August 27, 1909, which will be briefly described in connection with the subjoined specification in which is explained an example of vapor electric apparatus constructed 25 according to and containing the inventions and improvements claimed herein.

In the drawing hereto annexed there is shown an example of vapor electric apparatus which embodies our inventions.

30 In this drawing A is a metal container cylindrical in form and constructed of cold rolled sheet steel. The sides, top and bottom of this cylinder should be as thin as is consistent with the strength required to 35 sustain external atmospheric pressure, thus the total weight of the rectifier may be reduced, its manufacture facilitated and the radiation of heat from its body active except where it may be intentionally checked 40 by heat insulating contrivances if such are found desirable. At the top of the container there are secured tubular extensions B, B, B, all of which are preferably composed of cold drawn steel tubing. The top, 45 sides and bottom and also the tubular extensions are fitted together and then welded by means such as the oxyacetylene flame. Previous to the final fitting together of these parts a lining M composed of refractory insulating material, such as porcelain or 50 glazed lavite, is introduced into the container. This lining furnishes a suitable well for the reception of the liquid mercury cathode H. The other and further peculiarities and functions of this lining will be 55 explained hereinbelow. This lining, in structure and functional relationships with other portions of the apparatus forms the subject matter of an application for patent 60 Serial No. 569,694, filed by us on or about June 30, 1910, and are consequently not made the subject of claim herein.

The anodes E and F are composed of solid metal, preferably iron or steel, and are secured to the electrode leads E' and F'; the

lead E' consists of a metal rod, while the lead F' for the purposes to be alluded to consists of a tube of metal. The electrode leads are welded so as to form a completely tight joint as at D² with the iron or steel bonnet D. These bonnets are preferably cylindrical and of the same diameter as the tubular extensions B; the extensions B are provided with conical flaring ends B' and the bonnets D with similar conical flaring 71 ends D'.

The sealing joint is made between the tubular extensions B and the bonnets D in the following manner: The metal members being heated, a vitreous flux is fused upon the 80 surface of the conical extensions B', D', in such manner as to coat them thoroughly; this flux is preferably composed of borax which may have incorporated in composition with it, sodium glass and also ferric 85 oxid. Borax alone has the property of dissolving the oxids which form upon the surface of the metal, and of wetting and adhering to the metal itself, but the composition above described has not only this 90 property but is moreover more intimate in its adherence to iron or steel and possesses mechanical strength in a large degree. An insulating ring C which may be composed 95 of glass or other refractory insulating material, such for instance, as the semivitreous substance known as lavite, is placed between the conical extensions B' and D', the joints thereof being fused by means of the flux applied as above stated. If the insulating ring C is composed of material in any degree porous it should first be thoroughly coated or glazed with a refractory film which is thoroughly gas-tight. Thus 100 united, the tubular extensions B, the insulating rings C and the bonnets D, constitute 105 hoods between which and the electrode leads E', F' and G a space intervenes. Leads E', F', G, and all portions of the electrodes E and F, except the active ends, should be 110 incased in a refractory insulating covering E², F² and G', lest they form arcs or short-circuits undesirably. These insulating coverings may in some cases be made to adhere 115 by fusion directly to the metal surfaces to be protected; the vitreous composition, composed of about 60% soda glass, 25% borax and 12% ferric oxid, has been found eminently suitable to this purpose. The coating G' of the lead G should be carried well 120 below the surface of the mercury cathode H. The anode E shown in the drawing is smaller than the anode F, and approaches more closely to the cathode H, and this anode E, according to a system of electrical distribution invented by us, which forms 125 the subject matter of an application for United States patent filed by us on or about August 27, 1909, and serially numbered 514,907, may be employed in a merely aux- 130

iliary capacity so that the current conditions therein are not such as to heat the anode unduly. On the other hand, if as may well be the case the anode F operates under conditions which produce large quantities of heat, it is well to adopt provisions for regulating its temperature. In the drawing the anode F and its lead F' are shown as tubular; the tubular lead F' extends out through the insulating hood to the atmosphere. A small quantity of mercury H' is disposed in the bottom of the anode tube or in the hollow anode bulb, and by its evaporation and subsequent condensation upon the walls of the tubular lead F' will regulate the temperature of the anode F. (The tubular anode and provisions for regulating its temperature form the subject matter of an application for patent, Serial No. 569,698, filed by us on or about June 30, 1910.)

In the construction of a rectifier such as above described, after the electrodes have been introduced and the insulating joints perfected, the rectifier is heated and maintained at a temperature in the neighborhood of 500° C. and exhausted until a proper vacuum is secured. Devices for exhausting the rectifier, for introducing mercury, and for sealing the rectifier are not herein shown. The mercury is boiled out in the rectifier to remove traces of gas, or the rectifier may be put into electrical operation for the same purpose; after being finally sealed the rectifier is allowed to cool and is ready for use. It is highly desirable to pump out such a rectifier at a high temperature for the reason that appreciable quantities of gases are held in the metal walls and these gases are slowly given off into the

container at low temperatures, and the pressure in the container thereby eventually becomes too high for advantageous operation. By pumping out at high temperatures the delivery of these gases is greatly accelerated 45 and the gas exuding from the metal walls can be effectively removed.

The mode of construction above described enables the manufacturer of such apparatus to employ effectively permanently sealed insulated electrode leads of large size and capacity and to maintain these electrode leads effectively insulated so that the proper functions of the vapor electric apparatus may be performed consistently with the employment of a metal container which is obviously better qualified to resist the emergencies of transportation and use than any of the glass or porcelain containers heretofore suggested and employed. 50 55 60

What we claim and desire to secure by Letters Patent is:

In a vapor electric apparatus, a metallic container, an electrode therein, a metallic electrode lead, a tubular hood projecting 65 from the container and comprising two metallic portions, one integral with the container wall, the other integral with the electrode lead, and an annulus of insulating material between and sealed hermetically to 70 the two metallic portions of the tubular hood, the lead spaced on all sides from the inner surface of the tubular hood.

Signed by us at Boston, Massachusetts this 23rd day of August 1909.

CHARLES A. KRAUS.
ROY D. MAILEY.
